UNITED STATES PATENT OFFICE.

JOHN M. ROHLFING, OF PLAINFIELD, NEW JERSEY, ASSIGNOR TO AMERICAN CAR AND FOUNDRY COMPANY, OF NEW YORK, N. Y., A CORPORATION OF NEW JERSEY.

LADLE ELEVATOR.

Application filed May 7, 1923. Serial No. 637,209.

In the drawings:

Fig. 1 is a broken side elevation of the improved ladle elevator showing the supporting means used in connection therewith and 5 the relative positions of the elevator and the bull ladle;

Fig. 2 is a broken end elevation of the structure shown in Fig. 1;

Fig. 3 is a section taken on the line 3—3 10 of Fig. 1;

Fig. 4 is a broken vertical central section taken through the vertically moving part of the elevator and

Fig. 5 is a partial section taken on the line 15 5—5 of Fig. 4.

My invention relates to ladle elevators, and is adaptable and especially advantageous for handling pouring ladles in foundries,—in presenting and fitting them at the source 20 of supply of molten metal (as a bull-ladle), in transferring them to a conveyor for conveyance to the point where pouring is to be done, and in receiving them back from the conveyor for refilling.

25 In the embodiment of my invention here illustrated, the elevating mechanism or elevator A (Fig. 1) is mounted on a carriage 7 that is shiftable along a track 75. The track 75 is elevated, and the movable part 30 of the elevating mechanism A is suspended from the carriage 7 and arranged to be raised and lowered, as by means of an electric winch 13 on the carriage. The elevating mechanism A has a multiple ladle 35 "turret" support B at its lower end, rotatable about a vertical axis. As shown in Figs. 1, 2, and 3, a bull-ladle 55 to serve the pouring ladles 32 is located across the path of lateral movement of the mechanism A with the carriage 7, while an elevated conveyor track (monorail) C by which filled 40 ladles are carried to the point of pouring and returned leads off laterally from the mechanism A and the overhead carriage track 75, at a convenient distance from and 45 in front of the bull-ladle.

By raising and lowering the turret support B and rotating it, the pouring ladles 32 can be presented at a point in front of 50 and below the bull-ladle 55, where they can be filled, or transferred and presented at a point directly under the conveyor track C, where they can be attached to the traveller 57 thereon,—and vice-versa. By shifting 55 the mechanism A laterally toward and away

from the bull-ladle 55, the ladles 32 can be properly filled from the ladle 55 in all positions of the latter, whether tilted much or little, and can also be raised and lowered without striking the ladle 55 even with the 60 latter in the dot and dash position of Fig. 1. Such lateral shifting of the elevator A also allows the man who transfers ladles 32 from the elevator to the carrier 57 and vice-versa to be stationed further away from the heat 65 of the bull-ladle.

As shown in the drawings there is provided a support comprising columns 1 joined by cross braces 2 and supporting ends of horizontal members 3 which are secured to 70 the columns by means of angles 4 and braces 5. The horizontal members 3 have their other ends supported in the building wall 74 and carry rails 75 on which travel the wheels 6 of the overhead carriage 7. The wheels 75 6 are fixed upon axles 8 which are journaled in the side members 9 of the built-up frame 10 of the carriage 7. The frame 10 includes cross members 11 carrying upright members 12 upon which is mounted an electrically 80 operated hoisting device or winch 13 provided with a winding drum 14 about which a cable 15 is adapted to be wound by the operation of the hoisting device.

The elevating mechanism A is mounted 85 on the carriage 7 in the following manner:

Secured to the carriage frame 10 and projecting downwardly between the horizontal track-supporting members 3 are converging angle bars 16 which form an inverted pyramidal guide frame, being joined by the spacing members 17 and 18. Pivoted on the spacing members 17 and 18 are guide members or sleeves 19 and 20 having aligned cylindrical openings therein, 90 and having their supporting trunnions or pivotal axes in horizontal planes and at right angles to each other. Slidably mounted in the guides 19 and 20 is a tubular upright member 21 having a cap 22 secured to 100 its upper end and having its lower end secured to a cylindrical extension 23 formed on a yoke 24 in which a pulley 65 is mounted. The yoke 24 is also provided with a cylindrical portion 25 extending in the opposite direction to the extension 23 and having its lower end closed. The guidance afforded the upright 21 maintains it in definite angular relation to the carriage 7 and prevents it from swinging when the carriage 110

is moved, or the turret support B turned with a full ladle thereon.

The pouring ladle support B is rotatably mounted on the portion 25, and comprises a sleeve 26 provided with a flange 27 having diametrically opposite outwardly extended portions connected to the body of the sleeve by reenforcing ribs 28. Secured to the ribs 28 and the flange 27 at the outwardly extended portions are members 29 having a plurality of angularly disposed recessed lugs 30 adapted to receive the trunnions 31 of a pouring ladle 32. The sleeve 26 is also provided with an inwardly projecting flange 33 forming a shoulder which engages an upper roller journal bearing 34 which is held in place by a gasket 35. The gasket 35 is provided with a projecting flange 36 spaced from the portion 25 of the yoke 24 and providing a space in which is placed a packing 37 held in place by a packing gland 38. The gland 38 and the gasket 35 are secured in place by bolts 39 and 40. The lower portion of the sleeve 26 is provided with an annular flange 41 forming a shoulder on the sleeve against which is placed a gasket 42 which serves to hold in place a lower roller journal bearing 43 and which engages a sleeve-supporting ball bearing 44 mounted on the plate 45. The plate 45 is provided with a spherical recess having an opening at its center to receive a bolt 46 which is passed through an opening in the closed end of the portion 25 and receives a spherical washer 47 and nut 48 which hold the plate 45 in place and the sleeve 26 on the cylindrical portion 25 of the yoke 24. The opening in the annular flange 41 is closed by a cover 60 held in place by screws 61.

From the foregoing description, it will be seen that the sleeve 26 together with the arms formed by the outward extensions of its flange 27 and the members 29 constitute a strong supporting frame for the pouring ladles, by virtue of the fact that the radially projecting supporting arms are braced with reference to the sleeve both horizontally and vertically, by the flange 27 and the re-enforcing rib or web members 28 and 29. This frame is anti-frictionally journaled about the lower portion 25 of the upright 21 by the roller bearings 34 and 43, and is anti-frictionally supported by said upright through the ball-bearing 44.

The elevator *a* is raised and lowered by means of the electrically operated hoisting device 13, which operates the drum 14 to wind and unwind the cable 15 which passes from the drum 14 down through the carriage 7 and the guide frame formed by the parts 16, etc., to and around the pulley 65 and has its end secured to an angle bar 49 carried by the members 12. As the cable 15 thus "takes hold" on the upright 21 at the

pulley 65, below the guide frame, a liberal range of up and down movement of the upright 21 is practicable. To shift the carriage 7 upon the rails 75 there is provided a pulley 50 operated by a chain 51 and mounted on a shaft 52 journaled in the side plates 9 of the carriage 7. On the shaft 52 there is secured a pinion 53 which engages with a gear 54 secured on the adjacent axle 8.

In operation, an empty ladle 32 is positioned in front of the source of supply or bull ladle 55 and shifted back and forth by operation of the chain 51. When this ladle 32 is filled, the elevator *a* is raised by means of the hoisting device 13, bringing the lugs 30 up so as to engage the trunnions 31 of another empty ladle 32 held by the hooks 56 of the monorail carrier 57. The elevator *a* is raised further so as to lift this empty ladle 32 from the hooks 56 and is then rotated so as to place the ladle 32 already filled adjacent the hooks 56, whereupon the elevator is lowered to deposit this filled ladle 32 on the hooks 56. This filled ladle 32 is then conveyed to the pouring station by the monorail carrier or traveller 57, and the elevator *a* is lowered to bring a second empty ladle 32 into filling position before the bull ladle 55. In practice, a plurality of ladles 32 are used, so that all of the ladle positions but one on the ladle elevator are filled with ladles. Under this condition, the vacant position is filled by an empty ladle taken from the monorail carrier 57, and when the elevator is rotated to bring the filled ladle in line with the hooks 56 of the monorail carrier 57, an empty ladle is brought into position in front of the bull ladle. When the filled ladle is deposited on the hooks, a vacant position is made on the elevator to receive the next returned empty ladle. Lowering the elevator then places an empty ladle before the bull ladle in position for filling, the pouring ladle being shifted back and forth by the operation of the chain 51 in order that it may be properly positioned before the bull ladle as the bull ladle is tipped to fill the pouring ladle, the tipping of the bull ladle varying with the amount of molten metal it contains.

What is claimed is:

1. A shiftable turret elevator of the character described comprising a carriage, an upright movable up and down relative thereto, guide means for maintaining said upright in definite angular relation to the carriage, and a multiple ladle support rotatably mounted on said upright.

2. Apparatus of the character described comprising a carriage, an upright movable up and down relative thereto, guide means for maintaining said upright in definite angular relation to the carriage, means for raising and lowering said upright from the carriage taking hold on the upright below

said guide means, and a multiple ladle support rotatably mounted on the upright below said guide means.

3. Apparatus of the character described comprising a carriage, guide means thereon, an upright movable up and down in said guide means, and means for raising and lowering said upright including a pulley in a central opening in said upright and a hoisting cable through the same beneath said pulley.

4. An elevator of the character described comprising a carriage with a depending frame of pyramidal converging members carrying guide means, an upright movable up and down in said guide means, and a multiple ladle support rotatable about said upright below said guide means.

5. An elevator of the character described comprising a carriage with a guide frame thereon, an upright movable up and down in said frame with a multiple ladle support thereon, and upper and lower guides for said upright horizontally pivoted in said guide frame about axes at an angle to one another.

6. Apparatus of the character described comprising a vertically movable upright, a multiple ladle frame rotatable about said upright, an anti-friction supporting bearing for said frame carried by said upright, and an anti-friction journal bearing for the upper end of said frame around said upright.

7. Apparatus of the character described comprising a vertically movable upright, a sleeve rotatable about said upright, ladle supporting arms projecting from said sleeve, and webs bracing said arms to said sleeve both horizontally and vertically.

40 8. In combination with a bull ladle and a

ladle conveyor, a laterally shiftable elevator intermediate the bull ladle and said conveyor, and a ladle support secured to said elevator.

9. In combination with a bull ladle and a ladle conveyor, an elevator movable between said bull ladle and said conveyor, and a multiple ladle support rotatably secured to said elevator.

10. In combination with a bull ladle and a ladle conveyor, means for transferring ladles between said bull ladle and said conveyor comprising a shiftable carriage, an upright connected with the carriage and movable up and down relative to said carriage, and a ladle support mounted on the upright.

11. In combination with a bull ladle and a ladle conveyor, means for transferring ladles between said bull ladle and said conveyor comprising, a shiftable carriage, an upright secured to the carriage and movable up and down relative thereto, guide means for maintaining said upright in definite angular relation with respect to the carriage, and a ladle support mounted on the upright.

12. In combination with a bull ladle and a ladle conveyor, means for transferring ladles between said bull ladle and said conveyor comprising, a shiftable carriage, an upright secured to the carriage and movable up and down relative thereto, guide means for maintaining said upright in definite angular relation with respect to the carriage, and a multiple ladle support rotatably secured to the upright.

In witness whereof I have hereunto set my hand.

JOHN M. ROHLFING.
